DESIGN FOR A HIGHWAY AUTOMOTIVE PASSENGER VEHICLE

Clifford Brooks Stevens, Milwaukee, Wis.

Application December 18, 1937, Serial No. 73,697

Term of patent 14 years

To all whom it may concern:

Be it known that I, Clifford Brooks Stevens, a citizen of the United States, residing at Milwaukee, in the county of Milwaukee and State of Wisconsin, have invented a new, original, and ornamental Design for a Highway Automotive Passenger Vehicle, of which the following is a specification, reference being had to the accompanying drawing, forming part thereof.

I claim:

The ornamental design for a highway automotive passenger vehicle, as shown and described.

CLIFFORD BROOKS STEVENS.
